UNITED STATES PATENT OFFICE.

ANDREW PILLATT, OF NOTTINGHAM, ENGLAND.

FURNACE FOR WATER-TUBE BOILERS.

SPECIFICATION forming part of Letters Patent No. 605,511, dated June 14, 1898.

Application filed June 23, 1896. Serial No. 596,579. (No model.)

To all whom it may concern:

Be it known that I, ANDREW PILLATT, a subject of the Queen of Great Britain and Ireland, residing at Nottingham, England, have 5 invented new and useful Furnaces for Water-Tube Boilers, of which the following is a specification.

My invention relates to improvements in the furnaces of steam-boilers in which the 10 flame plays outside and around the water-tubes; and the object is to so construct and arrange these furnaces as to insure perfect combustion of the fuel-gases and promote economy and efficiency in working.

15 My improvements are particularly applicable to water-tube boilers of the Babcock & Wilcox, Hornsby, and like types.

In carrying out my invention I employ the hollow fire-bars, preferably those described 20 in the specification of my British Letters Patent No. 13,371 of 1895—that is to say, hollow fire-bars extending through and opening behind the fire-bridge and formed with series of air-inlets arranged in the web or rib there- 25 of. In combination with these bars I arrange in the upper part of the furnace a perforated refractory arch or roof of fire-brick, ganister, or the like, through the perforations in which the fuel-gases are drawn by the draft of the 30 chimney.

My invention will be readily understood by reference to the accompanying drawings, in which—

Figure 1 represents a boiler of the type mentioned fitted with my improved furnace. Fig. 35 2 is a plan, and Fig. 3 a transverse section, of the arch or roof, these figures being drawn to a larger scale than Fig. 1.

40 *a* is the refractory arch or roof, which may be formed in halves or sections, as indicated by the central division-line, Figs. 2 and 3, to facilitate fitting in the furnace, and is perforated with slots or openings *b* of any convenient shape and arrangement, whose total area 45 may advantageously be equal or approximately equal to the area for the passage of the furnace-gases between the water-tubes. The said arch or roof is arranged at a short distance below the water-tubes and at an inclina- 50 tion parallel with the said tubes. It springs from the side walls *c* of the furnace, where its edges are fitted in recesses *c'*, and extends from the furnace-front to the rear

wall *d*, so completely closing the upper part of the furnace save for the perforations above 55 mentioned.

e are the fire-bars, (with lateral openings *e'* in the web or rib,) which extend through an opening *d'* in the rear wall *d* and discharge highly-heated air into the products of com- 60 bustion as they pass down behind said rear wall.

When the arch and the fire-bars are in position, the products of combustion flow approximately in the direction indicated by the 65 feathered arrows, Fig. 1. The course of the heated air from the ash-pit through the hollow fire-bars to the space behind the rear wall *d* is as indicated by the plain arrows.

The arch *a*, by becoming highly heated, pro- 70 motes the combustion of the fuel-gases as they pass through the perforations in it, and the combustion is further assisted by the heated air from the hollow fire-bars *e*, with which the said gases meet and mingle. This air 75 having been drawn in through the lateral openings from the space between the bars has consequently a high temperature and insures the complete and instantaneous combustion 80 of all the carbon and other unconsumed matter in the fuel-gases, so entirely preventing smoke which has hitherto been a great objection to boilers of this class.

Having now described my invention, what I claim, and desire to secure by Letters Patent, is—

In a furnace for a boiler having water-tubes at an inclination above the bridge-wall, a perforated arch of refractory material over the fire-chamber and below the water-tubes of the 90 boiler, the back edge being closely adjacent to the bridge-wall, and hollow grate-bars having inlets for the air passing up from below the grate-bars and opening through the bridge-wall, so that the air is highly heated and combines with the products of combustion as they 95 descend from the perforated arch, substantially as set forth.

In witness whereof I have hereunto signed my name in the presence of two subscribing 100 witnesses.

ANDREW PILLATT.

Witnesses:

ANDREW ERNEST PILLATT,
C. D. HEARN, Jr.
